UNITED STATES PATENT OFFICE

2,571,270

SHIELDING DEVICE

Raymond R. Marchese, Pittsburgh, Pa.

Application December 19, 1949, Serial No. 133,924

2 Claims. (Cl. 69—20)

1

This invention relates to a shielding device adapted to be applied to fur scarfs or the like to cover and protect delicate parts thereof while the scarfs or the like are being cleaned.

Ordinarily, pieces of cloth are sewn over delicate parts of fur scarfs or the like, such as the snout and the artificial eyes thereof, to cover and protect such parts against damage while the scarfs or the like are being cleaned. Obviously, this entails the objectionable expenditure of considerable time and effort.

The primary object of the present invention, therefore, is to overcome this objection by providing a simple and durable shielding device which may be easily and quickly applied to or removed from the scarf or the like, which will effectively perform the intended function, and which may be re-used indefinitely.

The nature of the present invention will become apparent from the following description when considered with the accompanying drawing, in which:

Figure 1 is a fragmentary perspective view of a fur scarf having a shielding device applied thereto to protect the eyes and snout of the head portion of said scarf, said shielding devices being constructed in accordance with the present invention;

Figure 2 is an enlarged fragmentary view of the head portion of the scarf, partly in front elevation and partly in section, and showing in section the shielding device for one of the eyes;

Figure 3 is an enlarged view of the head portion, partly in side elevation and partly in section, and showing in section the shielding device for the snout; and,

Figures 4 and 5 are perspective views of the eye and snout shielding devices, respectively.

Referring in detail to the drawing, 5 indicates an ordinary fur scarf having a head portion 6 including a snout 7 and provided with artificial eyes 8.

The present shielding device includes a rigid cup 9 or 9' of a size and shape to fit over and cover the part to be protected, and a straight pin 10 rigidly attached at one end, as by soldering

or the like as at 11, to one side of said cup, so that the pin projects in the direction in which the open end of the cup faces. The cup 9 for the eye shield is of shallow segmento-spherical form, while the cup 9' for the snout shield is relatively deep and tapered slightly toward its closed end.

In use, the pin 10 is forced into the head portion 6 at one side of the eye 8 to be covered or near the outside of the snout to be covered, until the attached cup is positioned over the eyes as shown in Figure 2, or over the outer portion of the snout as shown in Figure 3. The pin effectively keeps the cup in shielding position, but accidental withdrawal of the pin may be additionally guarded against by roughening or notching the same as at 12.

It will be apparent that the device may be modified without departing from the spirit of the invention.

Having described the invention, what is claimed as new is:

1. The combination of a scarf fur facial organ and a shield, said shield comprising a rigid cup, and a straight pin rigidly attached at one side 25 of the cup, the pin projecting from the cup in the direction in which the open end of the cup faces and removably disposed in the scarf in such position that the scarf facial organ is covered.

2. A shield for fur scarfs which have at least 30 one animal facial organ, said shield comprising a cup adapted to cover the organ, and a straight pin fixed at one end to one side of the cup, the pin projecting in the direction in which the open end of the cup faces and arranged to pierce the scarf adjacent to said organ so that the cup overlies the organ to protect the organ.

RAYMOND R. MARCHESE.
